SORT VERIFIER FOR PUNCHED CARDS

Filed Dec. 18, 1950

UNITED STATES PATENT OFFICE

2,659,265

SORT VERIFIER FOR PUNCHED CARDS

Leo Patrick Martin, Decatur, Ill.

Application December 18, 1950, Serial No. 201,370

1 Claim. (Cl. 88—14)

1

The present invention relates to an improvement in a sort verifier for punched cards, such as illustrated, described and claimed in my prior patent application, Serial No. 175,335, filed July 22, 1950, now Patent No. 2,645,152, issued July 14, 1953.

While above application shows a mechanism that has proved especially efficient and durable in actual use, and practical and economical to manufacture, it nevertheless is the object of the present invention to provide an improved construction having still greater efficiency and durability in actual use, and being still more practical and economical to produce.

Another object is to provide a device of this type possessing facilities for ready attachment to and operation upon the conventional elongated glasswork top of known types of punched card sorting machines.

A further object is to provide in this improved device such structure and arrangement of parts as enable its use with a minimum of physical effort by the operator, while at the same time effecting rapid and accurate verification of punched cards.

My present invention, of course, is adapted for use with automatic electric card sorting machines of known types which present information resulting from their operation, as, for example, the sorting of punched cards into decks representing various classes, and enabling the stacking of individual decks of cards in neat and true arrangement for replacement in the sorting machine for successive sorting.

In practice, my improved invention enables the stacking, verifying, and general handling of whole sorted decks of punched cards in but a few moments time, with a maximum degree of accuracy, and it is necessary only to take the decks of sorted punched cards from the individual sorting pockets of the sorting machine, place them in the invention and true them up by butting the cards against the stop provision on the device, after which the back-plate thereof is raised, effecting the illumination of the electric light element within the device and enabling the sort to be verified by sighting through the punched holes in the stacked cards, which are normally in perfect register throughout the deck.

Of course, when by such procedure a hole is observed to be dark or blocked because of erroneously punched or sorted cards, the interfering card is removed from the deck.

It will appear obvious to those skilled in the art, that this improved sort verifier effects a con-

siderable saving of time, reduces operator fatigue to a minimum, eliminates injury to individual cards in the deck, and enables a maximum degree of accuracy in verifying the sort taken from the sorting machine.

With the foregoing and other objects and advantages in view, and which will become apparent as the invention is fully understood, its novelty resides in the construction, combination and arrangement of parts hereinafter specifically described, distinctly defined in the appended claim and illustrated in the drawings, wherein like reference characters refer to like parts throughout the several views.

15 Figure 1 is a top plan view of my improved sort verifier mounted on the right-hand end of the work-top (shown in fragment) of a card sorting machine.

20 Figure 2 is a front elevation of the arrangement shown in Figure 1, looking into the casement and showing a fragment of the window plate removed.

25 Figure 3 is a view taken transversely of Figure 2, partly in section, a fragment of one end of the casement being broken away, and showing the work-top of the sorting machine in section and broken apart to conserve space in the drawing.

30 Figure 4 is an elevational view similar to Figure 3, but with the front of the device raised for sighting through the punched cards in the deck which is shown in position.

35 Figure 5 is a perspective view of the window plate.

Figure 6 is a perspective view of my invention separate from the work-top of the sorting machine, and,

40 Figure 7 is a fragmentary view of a punched card of conventional type, showing a typical arrangement of punched holes therein.

45 A practical exemplification of my improved sort verifier may be seen in the following description and from reference to the accompanying drawings in detail wherein the numeral 10 designates generally the casement comprised of the bottom plate 11, the end plate 12, the end plate 13, the top plate 14, and the back plate 15, integrally assembled. Integrally mounted on the back plate 15 is one leaf 16A of the hinge 16, the other leaf 16B of which is adapted for integral engagement, usually with bolt means, to the rear portion of the frame member A of the work-top B of the sorting machine, which is not shown.

50 It is here noted that the frame member A and the work-top B are no part of the invention,

but are shown simply to facilitate the orientation thereof.

On the inner face of the end plate 13 is suitably mounted the electric socket element 17 by conventional nut and bolt means as at X, the incandescent lamp element 18 being threadably engaged in said socket element 17.

An electric "momentary contact" switch 19 is suitably mounted in the bottom plate 15, and is standard electric wiring designated generally as 10 at W provides electric power communication between said socket element 17, lamp element 18, switch 19, and electric wire connections W to effect the interior illumination of the casement 10 to direct light rays through the transparent window plate 20 and thence through the holes 15 alignedly positioned in the deck of punched cards designated by the numeral 21 for the purpose of sort verification.

The punched card 21' illustrated in Figure 7 20 illustrates one example of the usual punched hole arrangement in such cards. It will be understood, of course, from reference to Figure 4, that the cards shown in the deck 21 are so placed by the operator after having been sorted by the 25 sorting machine, and that such cards have punched holes which are in register throughout the deck, except in case an incorrectly punched or sorted card may be in the deck. It will be noted, too, that the bottom-plate 11 has formed 30 at its right-hand side edge the butt-plate 22.

The transparent window-plate 20 has the finger spaces 20A and 20B arranged in register with correspondingly located finger spaces 14' and 12' respectively in the top plate 14 35 and the end plate 12 as shown, to enable the operator to conveniently grasp the deck in order to place it in the device or to remove it therefrom as may be desired.

The window plate 20 has a pair of downwardly depending lugs 20C adapted for threadably engaging the screw members 23 protruding through suitable apertures in the front-plate 14, thus fixing the position of the window-plate 20, the peripheral edges of which, rest upon the edges of 45 the end-plates 12 and 13 and the top-plate 14.

In the practical application of my improved device, the operator removes the deck from the sort compartment of the sorting machine and places it upon the bottom-plate 11 so that the 50 bottom edges of the cards in the deck rest on said bottom-plate while the inner face of the deck rests flat against the outer face of the window-plate 20 (see Figure 4). The deck 21 being thus positioned, the operator need only 55 lightly press the left-hand end of the deck to bring its opposite end against the butt-plate 22 to effect the perfect alignment of the punched holes of the cards in the deck for verification. Then the operator grasps the foremost edge 24 60 of the bottom-plate 11 and lifts it to any convenient upwardly inclined position, which act

releases the pressure exerted by the back-plate 15 against the button 19' of the switch 19, thus completing the electric circuit in the wiring W and effecting the illumination of the lamp element 18 for sighting through the then aligned punched holes in the cards comprising the deck.

When the sort is verified the operator simply lowers the bottom-plate to its original position and this action brings the back-plate 15 again into contact with the button 19' which breaks the electric circuit, thereby extinguishes the light from the lamp element 18. It is hereby made obvious that no illumination is effected in the casement 10 until the operator is ready to sight through the deck, and also that the eyes of the operator are at all times protected from direct contact with the full light rays from the lamp element 18.

While I have set forth herein one embodiment of my invention, modification and change may be made in the same within the scope of the appended claim, and the structure and arrangement of parts together with their co-operative adaptation herein set forth and illustrated in the drawings is to be understood as non-limiting.

What is claimed is:

A sort verifier for punched cards comprising in combination hingedly mounted and raisable casement means carrying an illuminable element, said illuminable element being non-illuminated while said casement means remain in normal lowered stacking position and illuminated when in raised position, a transparent closure comprising one face of said casement means, means integral with said casement means for supportedly holding a deck of punched cards for sort verification in relation to the transparent closure comprising one face of said casement means, hinge means integral with the casement means for the purpose of hingedly mounting the casement means on the frame portion of a work-top of a card sorting means, switch means mounted in said casement means, a contact button on said switch means and adapted for releasable contact against said frame portion of said work-top for the purpose of effecting the off and on action of the switch means and said illuminable means carried by said casement means, depending on the position of said casement means.

LEO PATRICK MARTIN.
